UNITED STATES PATENT OFFICE.

JOHN C. HARPER, OF LINCOLN, NEBRASKA.

WORK-GUIDE FOR SEWING-MACHINES.

SPECIFICATION forming part of Letters Patent No. 742,867, dated November 3, 1903.

Application filed October 30, 1902. Serial No. 129,442. (5s model.)

To all whom it may concern:

Be it known that I, JOHN C. HARPER, a citizen of the United States, residing at Lincoln, in the county of Lancaster and State of Nebraska, have invented a new and useful Work-Guide for Sewing-Machines, of which the following is a specification.

The object of the present invention is to provide an improved form of work-guide in the nature of an attachment which may be applied to wax-thread machines of ordinary construction for guiding the work in the formation of rounds and other classes of leather goods, such as are used for reins and other portions of harness.

One of the principal objects of the invention is to provide a work-guide in which nearly all of the mechanism is disposed below the work-plate and out of the way of the operator and the stock. A further object is to provide an improved form of adjustable guide for properly supporting and holding the work in place during sewing, and a still further object is to insure the proper insertion and holding of the filling-in place in the outer portion of the leather without regard to the width of the filler.

A still further object of the invention is to provide the attachment with a channeling or grooving knife which may be adjusted to cut a groove at any desired position or of any desired depth in the leather.

A still further object of the invention is to so arrange the machine as to provide for the formation of bifurcated straps, such as are used for winker-braces and other portions of the harness.

With these and other objects in view the invention consists in the novel construction and arrangement of parts hereinafter described, illustrated in the accompanying drawings, and particularly pointed out in the appended claims.

In the drawings, Figure 1 is a perspective view of a work-guide attachment constructed in accordance with the invention. Fig. 2 is an inverted plan view of the same. Fig. 3 is a longitudinal sectional elevation of the work-guide. Fig. 4 is an end elevation of the same. Fig. 5 is a transverse sectional elevation of the guide on the line 5 5 of Fig. 2. Fig. 6 is a view similar to Fig. 1, showing the guide

adjusted for the manufacture of bifurcated straps and illustrating also the application of the adjustable channeling or grooving knife. Fig. 7 is an inverted plan view of the device with the parts arranged as illustrated in Fig. 6. Fig. 8 is a longitudinal sectional elevation of the guide on the line 8 8 of Fig. 7. Fig. 9 is a transverse sectional elevation of the device on the line 9 9 of Fig. 7.

Similar numerals of reference are employed to indicate corresponding parts throughout the several figures of the drawings.

The work-plate 10 of the attachment is provided with a plurality of openings 11 for the reception of the usual securing-studs formed on the National, Campbell, and other forms of wax-thread machine of well-known construction, and in said work-plate is also formed a transverse opening 12 for the passage of the usual awl and needle to form the stitches.

On the under side of the plate are a pair of undercut guides 14 for the reception of a longitudinally-movable slide 15, having a socket 16 for the reception of a pin 17, having a reduced end portion 18 extending through a guiding-opening in the rear portion of the slide. Surrounding the reduced portion of the pin is a compression-spring normally tending to force the pin outwardly, and this movement is limited by a stop-pin 19, secured to the pin and extending through a slot 20 in the slide. In the work-plate is an opening 21, extending longitudinally of the plate, and through said opening passes a block 22, secured at its lower end to the end of the pin 17. In order to accurately guide the block, the portion 23, which extends through the slot 21, is of a width just about equal to that of the slot, the walls of the latter preventing any lateral movement of the block. The block is provided with a threaded opening for the reception of the lower end of a stud or screw 24, on which is mounted a guiding-wheel 25, having a concaved periphery for engaging the curved surface of the leather and holding the same in proper position during the sewing operation, the compression-spring serving to hold the roller firmly against the work, while permitting some slight movement should there be any irregularity in the width of the material.

In the under side of the slide 15 is a slot 26, having rounded side walls and adapted for the reception of an operating-lever 27, pivoted on a screw 28 and adapted to engage with a holding-lug 29 on the under side of the bed-plate to hold the slide and roller against the work. When it becomes necessary to insert a fresh piece of work in position, the lever is depressed to an extent sufficient to release it from the lug 29, and it may then be moved to adjust the roller any required distance from the work. The lever is confined to the work-plate at one end in such manner as to cause its free end to spring upwardly, so that it would be held firmly in engagement with the lug 29 during the operation of the machine.

In the work-plate is formed a longitudinally-disposed slot 32, in which is guided a slide 33, the rear end of which is turned downwardly and secured to or formed integral with a pin 34, adapted to a guiding-opening in a block 35, secured to the under side of the work-plate. The pin 34 is acted upon by a compression-spring 36, normally tending to force the same in the direction of the concaved roller 25, and the end of the guiding-opening is threaded for the reception of a screw 37, whereby the stress of the spring 36 may be adjusted. Lateral play of the slide 33 is prevented by the side walls of the slot 32, and vertical movement is prevented partly by the pin 34 and partly by a plate 38, forming a portion of the work-plate and extending over the rear end of the slide. The front portion of the slide rests directly on the upper surface of the work-plate, and its movement in the direction of the transverse slot 12 is limited by an adjustable work-guide 40. The work-guide 40 is formed of a comparatively narrow strip of metal having widened and downwardly-turned end portions to engage with the side edges of the plate, and in one of the wider portions is a slot 41, through which extends a locking-screw 42 into an opening in the work-plate. This permits of the adjustment of the guide from and toward the needle-opening 12 to accommodate work of different character and afford a guide and rest for the material for the full width of the work-plate and at the same time adjusts the extent of forward movement of the slide 33.

For forming the ordinary rounds, such as shown in cross-section in Fig. 3, in which a filler is sewed between the edges of a bent piece of leather, I employ a pressing-roller 43 for engaging the edge of the filler and forcing the same into the bent strip, while the outer curved edge of said strip is acted upon by the concaved roller 25, and the two compression-springs act on the roller in such manner as to insure the forcing of the filling-piece into the bent strip of leather. The lower edge of the bent strip is properly guided by the guide-plate 40, and the row of stitching is therefore always parallel with this lower edge, while any unevenness or surplus mate-

rial will be forced beyond the line of the upper portion of the row of stitching in the direction of the roller 43.

In some classes of work, particularly in the formation of the bifurcated winker-braces, the roller 43 could not be employed if the stitching is to be carried up to the point of bifurcation, and to provide for this I employ an auxiliary guard in the form of a thin tapering tongue 46, having a laterally-projecting plate 47, which may be secured to the slide 33 in place of the roller. The metallic tongue, while not as efficient as the roller, permits the formation of the line of stitching close to the point of bifurcation.

In the manufacture of leather rounds it is usual to groove or score the leather to conceal the stitches and permit the cutting away and trimming of the edges of the leather in the subsequent treatment, one of the scoring-knives being carried by the presser-foot and the other by the work-plate. In the present instance I employ a scoring-knife 50, mounted on a pin 51, adapted to a suitable socket in a block 52, secured to the bottom of the bed-plate. The pin 51 may be moved longitudinally to effect the proper adjustment of the scoring-knife with respect to the stitching-forming mechanism and may be rotated in order to project the blade for a greater or less distance above the upper surface of the work-plate to form a groove of any desired depth.

The attachment is found convenient in that no portions of the mechanism except those in actual contact with the work are above the work-plate, the upper surface being perfectly clear and permitting the better manipulation of the stock than where the springs and carrying devices are on top of the plate.

While the construction herein described, and illustrated in the accompanying drawings, is the preferred form of the device, it is obvious that various changes in the form, proportions, size, and minor details of the structure may be made without departing from the spirit or sacrificing any of the advantages of the invention.

Having thus described the invention, what I claim is—

1. A work-guiding attachment for sewing-machines, comprising a slotted work-plate, a guided block disposed below the work-plate, means for adjusting the block longitudinally of the plate, a slide guided in one of the plate-slots and having a projecting pin adapted to a socket in the block, a spring tending to force the slide away from the block, a concaved guiding-roller mounted on said slide at a point above the work-plate and adapted to engage one side of the work, and a co-operative guiding device for engaging the opposite side of the work.

2. A work-guiding attachment for sewing-machines, comprising a work-plate having a longitudinal slot, a slide guided therein, a pin carried by the slide at a point below the work-plate, said pin having an end portion of re-

duced diameter, a guided block having a socket for the reception of said pin, a compression-spring surrounding the reduced portion of the pin and tending to force the pin from the socket, a stop-pin carried by said spring-pressed pin and extending through a slot in the block, a spring locking-lever pivotally connected to the under side of the work-plate and adapted to engage in a slot in said block, a locking-lug for engagement with said lever, a concaved work-guiding roller secured to the slide at a point above the work-plate and adapted to engage with one side of the work, and a co-operative guiding device adapted to engage with the opposite side of the work.

3. A work-guiding attachment for sewing machines, comprising a slotted plate, a slide guided therein, an auxiliary plate 38 forming part of the work-plate and tending to prevent

upward movement of the slide, a block secured to the under side of the work-plate and having a guiding-socket, a pin forming part of the slide and extending into said socket, a compression-spring disposed in the socket and bearing against the end of the pin, an adjustable screw carried by the socket and forming the opposite bearing for the spring, a work-guiding device secured to said slide at a point above the plate and adapted to engage with one side of the work, and a co-operative guiding device adapted to engage with the opposite side of the work.

In testimony that I claim the foregoing as my own I have hereto affixed my signature in the presence of two witnesses.

JOHN C. HARPER.
